US0D1067650S

(12) United States Design Patent (10) Patent No.: US D1,067,650 S
 Pence et al. (45) Date of Patent:  Mar. 25, 2025

(54) PAPER PRODUCT WITH SURFACE PATTERN

(71) Applicant: First Quality Tissue, LLC, Great Neck, NY (US)

(72) Inventors: Justin S. Pence, Williamston, SC (US); James E. Sealey, II, Belton, SC (US); Chris B. Anklam, Anderson, SC (US)

(73) Assignee: First Quality Tissue, LLC, Great Neck, NY (US)

() Term: 15 Years

(21) Appl. No.: 29/754,457

(22) Filed: Oct. 12, 2020

(51) LOC (15) Cl. 05-06

(52) U.S. Cl.

USPC D5/53; D5/58

(57) CLAIM

The ornamental design for a paper product with surface pattern, as shown and described.

DESCRIPTION

FIG. 1 is a top plan view of a paper product with surface pattern; and,

FIG. 2 is a bottom plan view thereof.

The broken lines surrounding the drawings depict the boundaries of the claim and form no part thereof.

1 Claim, 2 Drawing Sheets
